(57) **CLAIM**

The ornamental design for a recording and data storage medium, as shown and described.

DESCRIPTION

FIG. 1 is a perspective view of front, top and left side of a recording and data storage medium showing our new design; FIG. 2 is a perspective view of rear, top and right side thereof;

FIG. 3 is a perspective view of front, bottom and right side thereof;

FIG. 4 is a perspective view of front, bottom and right side thereof;

FIG. 5 is a perspective view of front, bottom and right side thereof;

FIG. 6 is a front view thereof;

FIG. 7 is a rear view thereof;

FIG. 8 is a left side view thereof;

FIG. 9 is a right side view thereof;

FIG. 10 is a top view thereof;

FIG. 11 is a bottom view thereof; and,

FIG. 12 is a bottom view with the lower cover removed thereof.

The portions of the article in broken lines are shown for illustrative purposes only and form no part of the claimed design. The dot and dashed lines illustrate a boundary of the claimed design and form no part thereof.

1 Claim, 10 Drawing Sheets
